(57) **CLAIM**

The ornamental design for an arrow shaped tile set, as shown and described.

DESCRIPTION

FIG. 1 is a top plan view of arrow shaped tiles showing my new design; and,

FIG. 2 is a perspective top view of the shown in FIG. 1, as fitted in an exemplary tile environment that comprises a series of individual tiles of the same design.

The broken lines are for illustrative purposes only and form no part of the claimed design.
